STERILE PACKAGE

Harry F. Waters, New York, N. Y.

Original application June 4, 1940, Serial No. 338,709. Divided and this application November 29, 1940, Serial No. 367,735

3 Claims. (Cl. 229—14)

The present invention relates to the packaging art, and, more particularly, to the art of packaging materials, including solid and liquid foodstuffs, in a sanitary and sterile manner.

As those skilled in the art know, collapsible packages and containers made of paper and of similar flexible materials were used to an ever increasing extent in the past. Generally speaking, these collapsible containers comprised a bag for holding the material to be packaged. This bag or envelope was frequently inserted into a carton to further reinforce the same and to impart a generally rectangular form thereto. This type of packaging offered great advantages, particularly when it was desired to package materials in such a manner as to hermetically seal them against the effect of external influences. In this case, generally, a fluid-tight and fusible liner was employed for making the inner container and bag and this liner was hermetically sealed by means of heat fusion of the fusible material or layer thereof. It has been found that containers of this type can be successfully employed even for packaging liquids.

The principal advantages of these fluid-tight containers resided in their low price, great strength and attractive appearance. In addition, this type of container could be shipped in a knock-down or collapsible form, whereby a very substantial saving in shipping space and cost could be obtained. While these fluid-tight collapsible containers practically revolutionized the packaging industry, some difficulty was experienced when packaging certain food-stuffs which have to be maintained in the condition of extreme purity. Such was the case particularly in packaging milk where it is imperative to maintain the milk in a completely pure and sterile condition. As is known, milk is an ideal breeding ground for micro-organisms of the most varied type and contamination of the milk causes great danger to the health of the consumer, including children and infants, having a relatively low resistance to infectious diseases. This problem was relatively simple to solve in the case of conventional milk bottles which could be sterilized before filling at high temperatures. By careful control of the manufacturing process, it was possible to obtain the initial purity and sterility of collapsible containers; there was no guarantee, however, against the introduction of germs, micro-organisms and other deleterious agents of an organic or inorganic character into the interior of the container during the time interval which elapsed between manufacturing

5 the container and filling the same. Due to the fact that the laws regulating the distribution and sale of milk and similar commodities are extremely severe, a serious problem existed in the packaging art in connection with the manufacture and use of collapsible milk containers.

It is an object of the present invention to provide a solution for the outstanding problem and to provide the art with a collapsible container for milk, and the like, which is capable of maintaining at least the same high standards of purity and sterility as may be maintained at present with conventional milk bottles.

It is another object of the present invention 15 to provide a method of sterile packaging which positively prevents the entrance of deleterious organic or inorganic impurities into the interior of the container intended for shipping and distributing milk and similar commodities.

20 It is a further object of the present invention to provide a novel and improved method of aseptical packaging which involves hermetically sealing the packaging medium immediately after it is manufactured, maintaining such seal 25 until such time as the package is filled with the commodity to be distributed, and thereafter resealing such package.

Still another object of the invention is the 30 provision of a novel and improved collapsible container which may be readily and hermetically sealed during its manufacture and which may be readily opened to perform the filling and resealing operation whereby said container is maintained in the time interval between its manufacture and ultimate use in a sterile and hermetically sealed condition.

The invention also contemplates a novel collapsible container for the purpose of aseptical packaging of foodstuffs, therapeutic agents, surgical cotton, and the like, which is simple in structure and which may be readily manufactured on a practical and commercial scale at a low price.

45 Other and further objects and advantages of the invention will become apparent from the following description, taken in conjunction with the accompanying drawings in which:

50 Fig. 1 illustrates a plan view of a blank for the purpose of manufacturing a container embodying the principles of the present invention;

Fig. 2 depicts a similar view of the blank shown in Fig. 1, having a liner adhesively secured thereto;

Fig. 3 shows a top elevational view of a container embodying the invention during one of

its preliminary steps of manufacture in which the two halves of the carton blank and layer are folded together and the resulting envelope is heat-sealed;

Fig. 4 is a perspective view of the container of the invention in its finished and collapsed condition ready for shipment and storage;

Fig. 5 illustrates a perspective view of the container of the invention in its squared-up condition and ready for the filling operation;

Fig. 6 depicts a similar view of the container having the mouth portions of the inner envelope or bag flattened into a face to face relationship;

Fig. 7 shows a perspective view of the container with the top marginal portions of the inner bag bent upwards for the purpose of hermetically sealing the content thereof;

Fig. 8 is a similar view of the container after the heat-sealing operation showing the resulting tabs folded towards each other, the flaps of the carton being illustrated in their opened condition for reasons of clarity.

Broadly stated, according to the principles of the present invention, the entrance of micro-organisms into the interior of a collapsible container is positively prevented by hermetically sealing the filling opening of the container during or immediately after its manufacture and maintaining the container in such hermetically sealed condition until the time it is to be filled. Due to the presence of such hermetic seal, the entrance of deleterious matter of any description is rendered impossible because even though such matter might be of a microscopic character, the hermetic seal will offer an effective obstacle against its entrance. Thus, while in prior practice the interior of collapsible containers was exposed to germs, and the like, during shipment and storage, such contamination of the container is rendered impossible by my invention.

My invention may take various forms in accordance with the type of container contemplated. Thus, in the simplest case where the collapsible container is of the heat-sealed envelope type, I prefer to employ a flexible sheet which is fluid-tight and fusible on at least one face thereof and is folded over along a medial line to bring its edges into registering position. This operation leaves three open edges which may be individually heat-sealed by applying heat and pressure along a narrow marginal strip thereof. In most cases, however, it is preferred to apply this heat-seal simultaneously to all of these three marginal portions in the shape of a continuous and U-shaped heat-seal which hermetically seals the interior of the envelope against external influences. In this condition the envelope may be preserved in a sterile and unaffected condition, indefinitely. When it is desired to fill this envelope with material of any description, a restricted opening may be made therein or for example, a narrow strip including one of the heat-sealed seams may be cut off to provide a filling opening. Through this filling opening the contents may be introduced and then the envelope may be resealed. As a rule, it will be preferred to employ an envelope or bag in combination with an outer supporting carton which imparts additional strength to the inner bag or envelope. In my application, Serial No. 329,254, filed April 12, 1940, I have described collapsible containers of this type, all of which are adapted for hermetically packaging various commodities, including milk. Generally, a carton blank of suitable character is provided to which a liner fusible on at

least the top surface thereof is adhesively secured. The carton blank and the liner are so constructed and arranged that manipulating and folding the carton along predetermined score lines will cause folding of the liner into a position in which it may be heat-sealed while it is still resting on the carton blank. While in prior practice this folded liner was heat-sealed along only two of its edges to retain a filling opening,

10 in accordance with the present invention the folded liner is completely sealed along all three edges whereby a completely and hermetically sealed structure is provided. In order to permit removal of a portion of this inner bag or envelope of completely sealed character and still retain a sufficient marginal portion for resealing, it is desirable to have the liner extend slightly longer than this was necessary or customary in prior practice. On the other hand, since for simplicity of manufacture it is desirable to heat-seal the liner while resting on the carton blank of the container the upper flaps associated with the blank have to be slightly extended corresponding to the extension of the liner. This makes it possible to cut off a strip of the finished and collapsed carton and liner in a single operation and thereby to prepare the container for filling, as this will be explained more fully as the description proceeds.

30 Referring now more particularly to the drawings, a preferred embodiment of the invention will be explained. Fig. 1 illustrates a plan view of a carton blank 10, having a plurality of score lines defining main panels 11 and 12 and end panels 13 and 14. Flaps 15 and 16 are hingedly connected with main panels 11 and 12, respectively. Flaps 17 and 18 are provided at the ends of end panel 13 and similar flaps 19 and 20 are provided at the ends of end panel 14. It will be noted in Fig. 1 that main panels 11 and 12 are connected by means of a bottom panel 21 of special character having a medial score line 21a permitting the carton blank to be folded so as to bring the main panels into a substantially registering position. Main panel 12 has glue flaps 22 and 23 at the two lateral edges thereof. End panels 13 and 14 have medial score lines 24 and 25 respectively. A carton blank of this general type is disclosed in my copending application, Serial No. 255,030, filed on Feb. 7, 1939, so that no detailed description of its operation will be necessary. It will be sufficient to state that by bringing the main panels into superposed registering position and by folding back the portions of the end panels beyond medial lines 24 and 25, such portions of the end panel may be glued to glue flaps 22 and 23 of main panel 12 whereby a flattened six sided box is obtained capable of being converted or squared-up into a rectangular package. It is to be observed that top flaps 15, 17 and 19 are considerably longer than the corresponding flaps 18, 20 and 21. The object of the accentuated length of these flaps is to provide a backing surface of a liner of likewise accentuated length which at a later time is converted into a structure of standard length by cutting off the excess length, as this will appear more fully hereinafter.

70 The first step in the preparation of my improved sterile collapsible container is to adhesively secure a liner 26 to the carton blank by means of adhesive lines 27. As it will be best observed in Fig. 2, this liner is generally constituted of a rectangular sheet of flexible material, fusible and fluid-tight on at least the upper surface

thereof. The liner has such dimensions as to extend from the region of score line 21a of carton blank 10 substantially up to the top edge of such blank and to extend the same distance in the opposite direction. Laterally the liner extends across about three-fourths of the width of end panels 13 and 14 and beyond medial lines 24 and 25. After this liner has been secured to the carton blank in the proper position, the carton blank and the liner attached thereto are simultaneously folded along score line 21a thereby providing the structure depicted in Fig. 3. This operation will fold the liner along its transverse medial line and will bring its edges into registering position. At the same time main panels 11 and 12 will likewise be brought into a superposed registering position and will have the folded liner therebetween. It is of great importance that in this position of the carton blank and liner, the marginal portions of the liner are exposed so that they are accessible to a heat-sealing device of appropriate character. To maintain the sterile character of the folded liner, I heat-seal the liner at this stage of manufacture and thereby positively prevent the admittance of deleterious agents to the interior surface thereof. This hermetical seal may be accomplished for example by applying heat and pressure in separate operations along each of the exposed marginal strips of the folded liner. As a rule, however, I prefer to apply a continuous U-shaped seam to these marginal portions by means of a special U-shaped heat-sealing member so that a continuous hermetical seal 28 will be obtained. This seal converts the folded liner sheet 26 into a completely sealed envelope into which the access of any external substance, including that of atmospheric air, is prevented. End panels 13 and 14 are now folded along their medial score lines 24 and 25 and their inner surface is adhesively secured to glue flaps 22 and 23 of main panel 12. It will be noted that folding of the end panels along their medial score lines will cause folding of the sealed envelope about the edges of glue flaps 22 and 23 so that a fold will be introduced into the portion of the envelope before the seam. This will protect the seam from the effect of internal pressure after the container has been filled and sealed.

The finished container in its collapsed form, as it is shipped and stored, is shown in Fig. 4. Due to the fact that in this condition the inner envelope is completely sealed, the container may be preserved in the sterile condition indefinitely. A further interesting result of this completely sealed structure is that the external atmospheric pressure prevents squaring-up the collapsible container due to the fact that no air is admitted thereto and squaring-up would create a vacuum therein. In other words, the containers of the invention will be automatically maintained in a completely flattened condition which is an important advantage in that it reduces the space required for shipping and storage of the containers to a minimum.

When it is desired to use and to fill the container, it is necessary to provide a filling opening therein through which first air may be admitted into the interior, permitting squaring-up of the container and subsequently the filling operation may be performed and the filled container may be resealed. The filling opening may be provided in various ways, such as by punching a small opening or by cutting off one of the edges of the container, as this is indicated by dotted

line 29 in Fig. 4. It is preferred, however, to cut off a transverse marginal portion of the inner envelope, and the container shown in the drawings is especially adapted for this type of manipulation. According to this preferred procedure, a top marginal strip 30 of the collapsible container is removed by cutting the container along a line 31 indicated in dotted lines in Fig. 4. This operation will remove the top marginal portions of both the inner envelope and of the external carton. This will have the result of admitting air into the interior of the envelope and at the same time removing the excess portions of top flaps 15, 17 and 19 which will now have the same length as the corresponding bottom flaps 18, 20 and 21. The flattened container may now be squared-up and assumes the shape illustrated in Fig. 5. It will be noted that the squared-up and opened envelope has two lateral fins 32 and 33 which are flattened in the direction of the end panels 13 and 14. The material to be packaged, such as, milk, cream, or some other commodity, may now be introduced through a filling spout 34 connected with a storage tank and with a suitable measuring device which introduces a predetermined unitary amount of the material to be packaged.

I have found that in order to provide a hermetical seal of the package and to positively prevent leakage from such sealed package, it is critically important to provide a seal of such character in which only two layers of material are placed into a face to face relation and from which intervening layers, re-entrant folds and similar danger points of leakage are positively eliminated. Therefore, in order to obtain the desired hermetical seal and the face to face relationship of only two layers of material in the mouth portions of the envelope, a special procedure has to be used. This consists in bringing together the flattened mouth portions of the envelope into a face to face relation and folding down the resulting flattened mouth portions into the plane defined by the hinge lines of the top flaps. Attention is directed to the circumstance that this folding down of the flattened marginal portions is possible only in the direction in which fins 32 and 33 are pointing due to the fact that these fins act much in the same manner as reinforcing ribs which are almost completely rigid in other directions. This operation provides the structure depicted in Fig. 6. Of course, the top marginal strip 35 of the package embodying the invention may be heat-sealed already in this position by means of a heat-sealing device of suitable character. Generally, I prefer, however, to fold this region 35 to be heat-sealed vertically upwards, (Fig. 7), whereby it is more readily accessible to a heat-sealing member and backing member of standard type. It will also be noted that region 35 represents a completely flat seal area in which even the terminal portions of fins 32 and 33 are straightened out in the direction of the mouth walls of the envelope where by the critically important completely flat seam may be readily obtained. After heat-sealing, the resulting tabs 36 and 37 may be folded towards each other along lines 38 and 39 as this is shown in Fig. 8 and the flaps of the carton may be closed and adhesively secured thereabout. This completes the package of the invention.

It will be noted that the present invention provides important advantages. The method of the invention makes it possible for the first time in the history of the art to maintain the originally

sterile condition of a collapsible container until the filling operation and to positively prevent the contamination of the interior of the container by micro-organism. Of course, this is of extreme importance particularly when it is desired to employ collapsible containers for the purpose of packaging milk, cream and similar foodstuffs which have to be distributed under conditions of extreme purity.

It is also to be observed that while my novel method is applicable to practically any type of collapsible container formed by means of ordinary adhesive or with fusible and reactivable adhesives, I have also disclosed certain specific and preferred forms of containers which are especially adapted for carrying the principles of my invention into practice.

Moreover, the special sterile containers disclosed herein are extremely simple in character and may be manufactured, sold and used on a practical and commercial scale at a very low price.

Although the present invention has been described in connection with a few preferred embodiments thereof, variations and modifications may be resorted to by those skilled in the art without departing from the principles of the present invention. I consider all of these variations and modification as within the true spirit and scope of the present invention, as disclosed in the foregoing description, and defined by the appended claims.

The present application is a division of my pending application Serial No. 338,709, filed June 4, 1940, and which has resulted in Patent No. 2,223,754 granted Dec. 3, 1940.

I claim:

1. A sterile packaging unit which comprises a four-walled carton blank having medial score lines in two oppositely disposed walls thereof, a substantially rectangular liner secured to said blank having at least its top surface fluid-tight and fusible, folded over along one of said medial score lines together with said blank to bring the edges of said liner into substantially registering position, a heat-sealed seam hermetically sealing said liner and positively preventing the admittance of deleterious matter thereinto, and an adhesive bond securing the ends of said carton blank together, the flap portions of said carton blank being so constructed and arranged as to

provide a supporting surface for the top terminal portions of the liner during the heat-sealing operation, said hermetically sealed liner being adapted to be preserved indefinitely in its original collapsed and sterile condition and capable of being opened by cutting off a marginal strip thereof together with a corresponding strip of said carton and of being squared-up, filled and resealed.

2. A paperboard container, which comprises a flat-folded sheet of flexible material folded in and secured by a carton blank having a common fold line, said carton blank having front and back wall panels in register and side wall panels, each of these said panels being adhered to the liner sheet, the said carton having top closure tabs extending from the side wall panels and the main wall panels, the liner sheet having its marginal edges in register and sealed, and the top or mouth portion of the envelope formed having excess material, the marginal edge of the oversize mouth section being sealed thereacross to seal off the interior of the envelope, the side wall panels being folded over and secured to form a flat-folded container, and the top seal of the envelope being adapted to be removed and permit filling of the container and resealing of the mouth of the envelope.

3. A paperboard container, which comprises a flat-folded sheet of flexible material having at least its inner surface with marginal heat-sealable portions and folded in and secured by a carton blank having a common fold line, said carton blank having front and back wall panels in register and side wall panels, each of these said panels being adhered to the liner sheet, the said carton having top closure tabs extending from the side wall panels and the main wall panels, the liner sheet having its marginal edges in register and heat-sealed, and the top or mouth portion of the envelope formed having excess material, the marginal edge of the oversize mouth section being heat-sealed thereacross to seal off the interior of the envelope, the side wall panels being folded over and secured to form a flat-folded container, and the top seal of the envelope being adapted to be removed and permit filling of the container and resealing of the mouth of the envelope.

HARRY F. WATERS.
